Patented Sept. 4, 1956

178,626

TOY WATER GUN

Charles Arliss, Bayside, N. Y.

Application February 9, 1956, Serial No. 40,097

Term of patent 7 years

(Cl. D34—15)

FIG. 1

FIG. 2

FIG. 3

FIG. 4

FIG. 5

Fig. 1 is a side view of a toy water gun showing my new design;

Fig. 2 is a view of the side opposite that shown in Fig. 1;

Fig. 3 is a rear view of the water gun shown in Figs. 1 and 2.

Fig. 4 is a perspective view of the toy water gun shown in Figs. 1, 2 and 3; and

Fig. 5 is a front view thereof.

I claim:

The ornamental design for a toy water gun, substantially as shown.
